UNITED STATES PATENT OFFICE.

WILLIAM F. KEISER AND CHARLES RYAN, OF TERRE HAUTE, INDIANA.

CAR-DOOR.

1,092,108.

Specification of Letters Patent. Patented Mar. 31, 1914.

Application filed December 31, 1913. Serial No. 809,691.

To all whom it may concern:

Be it known that we, WILLIAM F. KEISER and CHARLES RYAN, citizens of the United States, residing at Terre Haute, in the 5 county of Vigo and State of Indiana, have invented new and useful Improvements in Car-Doors, of which the following is a specification.

This invention relates to improvements in 10 sliding doors, such as freight car doors, and especially with reference to means for hanging a door of this class and for securing the door whether in open or in closed position so as to prevent it from rattling and 15 also prevent the door from moving casually from closed or open position, the invention consisting in the construction, combination and arrangement of devices hereinafter described and claimed.

20 In the accompanying drawings: Figure 1 is a side elevation of a portion of a railway freight car provided with a sliding door constructed in accordance with our invention and showing the door in closed position. Fig. 2 is a vertical sectional view of 25 the same on the plane indicated by the line *a—a* of Fig. 1. Fig. 3 is a side elevation of the same showing the door in partially open position. Fig. 4 is a vertical sectional view 30 of the same on the plane indicated by the line *b—b* of Fig. 3.

For the purposes of this specification a car wall is indicated at 1, provided with a door opening 2 and also with stops 3 and 4, 35 the stop 3 being arranged near one side of the door opening and the stop 4 being spaced a suitable distance from the opposite side of said opening. On the wall, at a point lower than the door opening, is a 40 guiding and supporting track rail 5 which is here shown as substantially trough-shaped in cross section and as comprising an inner vertical web 6 which bears against and is secured to the wall, a horizontally arranged 45 bottom tread 7 and an outer vertically arranged flange or web 8, the said outer flange or web being provided at opposite ends with substantially semi-circular upwardly extending cams 9—10 and being provided at 50 a point near the center with a similar cam 11. The cam 9 is arranged near the stop 3 and the cam 10 is arranged near the stop 4. The distance between the cams 10 and 11 is somewhat greater than between the cams 9 55 and 11.

The door 12 is provided at its upper side

with guides or hangers 13 which project upwardly therefrom and the upper ends of which engage the inner side of a guide rail 14 which is arranged above the door opening, extends from the stop 3 to the stop 4 and is spaced a slight distance from the wall. At the lower side of the door, at its corners, are a pair of carrier frames 15 which are H-shaped in cross section as each carrier frame comprises a bar or web 16 to bear against the under side of the door, a pair of upwardly extending lugs 17 to bear against and which are screwed or bolted to opposite sides of the door and a pair of 60 downwardly extending standards 18 in which the axles 19 of a pair of supporting rollers 20 are mounted. Said supporting rollers operate in the trough-shaped track rail 5, bear normally on the tread 7 thereof and are arranged between the web 6 and the flange 8. Each carrier frame has its outer standard 18 provided with a horizontally arranged outstanding tappet flange 21.

The operation of our improved door and door supporting means is as follows: When the door is moved to closed position the rollers travel on the tread 7 of the rail 5 until the carriers reach the cams 9 and 11 which occurs just before the door reaches a 65 fully closed position. As the door is moved to fully closed position the tappet flanges 21 of the carriers ride upwardly on the cams 9 and 11 thus slightly raising the door and wedging it between the guide rail 14 and the said cams. When the door is in fully closed position the tappets 21 are slightly to one side of the centers of the cams and hence not only is the door wedged and held against rattling, but the door is caused to press by 70 its own weight against the stop 3, owing to the tendency of the tappets 21 to slide forwardly on the cams 9 and 11, and hence the door is held in closed position against casual movement. When moving the door to open 75 position it lowers by its own weight as soon as the carrier tappets pass the cams 9—11, so that the rollers 20 become reengaged with the tread 7 of the track rail 5. As the door nears open position one of the carriers reaches the cam 11 before the other carrier reaches the cam 10, and the first-named carrier by reason of the engagement of its tappet flange therewith rides over the cam 11 and reaches the rear side of said cam at the 80 same time that the tappet flange of the other carrier rides upwardly on the cam 10 and

serves to wedge the rear end of the door. The first named carrier by reason of its being entirely past or to one side of the cam 11 holds the door in open position against 5 casual movement of the door so that the door can neither rattle nor slide casually.

Having thus described our invention, we claim:—

1. In a structure of the class described a 10 track rail having upwardly extending cams, a guide rail, and a door mounted for sliding movement on the track rail and having engagement with the guide rail, the door being also provided with tappets to engage the 15 said cams and cause the door to be moved upwardly and held against casual movement by the engagement of its tappets with the cams when the door is in open position or in closed position.
- 20 2. In a structure of the class described the combination of a track rail having a tread, an outer flange and cams on and extending upwardly from said outer flange, in combination with a guide rail, and a door slid- 25 ably connected to the guide rail and pro-

vided with supporting rollers to operate on the tread of the track rail, the said door also having tappets to engage the cams of the track rail and coact therewith to raise and wedge the door when in open or closed 30 position.

3. In a structure of the class described the combination of a track rail having a tread and also having a flange and spaced cams extending upwardly from the flange, in combination with a guide rail, a door slidably connected to the guide rail, and carriers on the lower side of the door, the carriers being provided with rollers to operate on the tread of the track rail and with tappet 40 flanges to engage the cams when the door is in open or closed position, for the purpose set forth.

In testimony whereof we affix our signatures in presence of two witnesses.

WILLIAM F. KEISER.
CHAS. RYAN.
